(57) **CLAIM**

The ornamental design for a wireless card reader, substantially as shown and described.

DESCRIPTION

FIG. 1 is a perspective view of a first embodiment of a wireless card reader showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a perspective view of a second embodiment of the wireless card reader; and,

FIG. 9 is a top plan view thereof.

The front, rear, right side, left side elevational views and the bottom plan view of the second embodiment of the wireless card reader are the same as those of the first embodiment and, therefore, are not shown.

1 Claim, 5 Drawing Sheets
